SKATE

Glendon M. Pomeroy, Worcester, Mass., assignor
to Matthews Manufacturing Company, Worcester, Mass., a corporation of Massachusetts

Application June 21, 1934, Serial No. 731, 693

2 Claims. (Cl. 208—173)

The principal objects of this invention are to provide means for strengthening a shank which holds together the heel and toe plate of a roller skate without increasing the cost thereof, and to 5 provide a better way to fix the shank to the heel and toe plate.

Other objects and advantages of the invention will appear hereinafter.

Reference is to be had to the accompanying 10 drawings, in which

Fig. 1 is a plan of a roller skate constructed in accordance with this invention;

Fig. 2 is a side elevation of the upper part thereof;

Fig. 3 is a plan of a part of the toe piece of the skate removed from the other parts;

Fig. 4 is a sectional view on the line 4—4 of Fig. 1;

Fig. 5 is a plan of the shank removed from the 20 rest of the skate;

Fig. 6 is a transverse sectional view on the line 6—6 of Fig. 5;

Fig. 7 is a longitudinal sectional view on the line 7—7 of Fig. 1 of the shank, on enlarged 25 scale;

Fig. 8 is a similar view on the line 8—8 of Fig. 1 of the heel piece, on enlarged scale;

Fig. 9 is a plan showing the application of 30 this invention to a different type of skate;

Fig. 10 is a side view of the same;

Fig. 11 is a plan of the front part of the heel piece;

Fig. 12 is a plan of the rear part of the toe piece;

Fig. 13 is a sectional view on the line 13—13 of Fig. 9, and

Fig. 14 is a sectional view on the line 14—14 of Fig. 9.

The end pieces of the roller or ice skate 40 comprise a toe piece 10 and heel piece 11, each provided with mountings 12 and 13 respectively for receiving the rollers, which are not shown. In the first sheet of drawings the end pieces are both provided with longitudinal flat grooves 14 and 15 respectively on top making, of course, corresponding flat projections 16 on the bottom with slanting sides. These grooves 14 and 15 are wide and shallow and they are provided with corrugations or square edged teeth 17, which are formed, as shown in Fig. 8, by a die pressing or punching process which brings a series of parallel teeth to the top and bottom respectively of the sheet metal of which the toe piece and heel piece 50 are made. In each case this shallow groove

is provided with a square or other non-circular perforation 18.

The shank piece 20 is formed of sheet metal having a central plane portion and provided with flanges 21, which are bent around in the form of hollow substantially cylindrical beads extending therealong. These beads serve two purposes. First, they strengthen the shank piece, which is formed of a relatively light sheet metal, against bending in a longitudinal direction, and second, these beads serve as side walls to come 10 against the walls of the projections 16 of the end pieces 10 and 11. This prevents shifting sideways of the connected parts.

The shank piece is provided with two slots 15 22 and 23 longitudinally placed and spaced apart and is also provided with square edged teeth 24 on the bottom and top like the teeth 17 and formed in the same way. These teeth serve two purposes, first, to provide means for engaging 20 the teeth 17 and hold the two slidably connected parts together in firm relationship and second, to strengthen the shank piece against bending in a transverse direction. The shank piece 20 can be adjusted to project from the rear of the heel piece as far as desired, so it allows a wide 25 range of adjustment.

To hold these three parts together a pair of bolts 25 and 26 are employed extending through the square holes 18 and the slot 22 or 23. On the under side each bolt is provided with a nut 27 30 and a washer 28. The parts are adjusted to the position shown to provide a skate of the desired length and the nuts are screwed up to hold the three parts together. As the washer and the 35 head of the bolt both engage the corrugated surfaces the nuts can be tightened up firmly and will hold the parts together in a strong and permanent manner.

The provision of the beaded sides of the shank 40 piece 20 fitting the slanting walls on the projections of the bottom of the heel piece and toe piece further prevents displacement of the parts. Even if the nuts become loosened a little, they will keep the parts in proper relationship for a 45 time. The shank piece is made strong in both directions by the beads and corrugations without increasing the amount of metal in it or the expense of manufacture. It also is so constructed on account of the corrugations as to 50 facilitate adjustment and the tightening of the parts after adjustment. This constitutes a simple and inexpensive skate having improved strength and increased ability to withstand twisting 55

strains without displacing the toe piece or the heel piece from the shank.

In the form shown in the second sheet of drawings, certain features of this invention are shown as applied to another type of roller skate in which the toe piece 30 and heel piece 31 are provided respectively with projections or tongues 32 and 33, the former having a slot 34 and the latter a perforation 35^a for fastening bolts 36. These projections 32 and 33 overlap each other and they are provided with the same kind of corrugations or teeth 35 as have been described. The toe piece is slightly slanted at 36 and provided with a slot 37 through which the end of the tongue 33 can pass. The end of the tongue 33 is provided with an open-ended slot 38 so that the two parts can be adjusted close together and the end can pass beyond the stationary guard 39 for the adjusting screw 40. The sides of the toe piece are bent over downwardly to form heads 41 located entirely below the upper surface thereof. This may extend any desired distance and preferably extends through out the straight sides of this member. The beads constitute means for strengthening it because

it cannot be strengthened by a longitudinal rib in the center very readily on account of the teeth or corrugations. The functions of the new features in this form of the invention are substantially the same as those described in connection with Sheet 1 of the drawings.

Having thus described my invention and the advantages thereof, I do not wish to be limited to the details disclosed, otherwise than as set forth in the claims, but what I claim is:—

1. As an article of manufacture, a shank piece for a skate consisting of a sheet metal piece having its longitudinal edges in the form of hollow substantially cylindrical beads extending the length of the shank piece.

2. As an article of manufacture, a shank piece for a skate consisting of a sheet metal piece having its longitudinal edges in the form of hollow substantially cylindrical beads and transverse square edged corrugations on the top and bottom surfaces, extending from one bead to the other, the shank piece having two separated longitudinal slots for receiving fastening devices.

GLENDON M. POMEROY. 25
